US0D1001572S

(12) **United States Design Patent** (10) Patent No.: **US D1,001,572 S**
(45) Date of Patent: ** Oct. 17, 2023

(54) **FOOD GRINDER**(71) Applicant: **WHIRLPOOL CORPORATION**,
Benton Harbor, MI (US)(72) Inventors: **John W. McConnell**, St. Joseph, MI
(US); **Nicholas H. Schutte**, St. Joseph,
MI (US); **Brandon T. Mock**, St.
Joseph, MI (US)(73) Assignee: **WHIRLPOOL CORPORATION**,
Benton Harbor, MI (US)(***) Term: **15 Years**(21) Appl. No.: **29/888,280**(22) Filed: **Mar. 29, 2023**

CLAIM

The ornamental design for a food grinder, as shown and described.

DESCRIPTION

FIG. 1 is a top-front perspective view of a food grinder according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a back-bottom perspective view thereof.

The portions of the article shown in even broken line form no part of the claimed design.

Dash-dot-dash broken lines adjacent un-shaded areas represent bounds of the claimed design and form no part of the claimed design themselves.
